United States Patent

Des. 242,241

Patented Nov. 9, 1976

242,241

PORTABLE COMPUTER ROOM OR SIMILAR ARTICLE

William J. Bowman, Menlo Park, Calif., assignor to
Xerox Corporation, Stamford, Conn.

Filed Mar. 3, 1975, Ser. No. 554,363

Term of patent 14 years

Int. Cl. D25—03

U.S. Cl. D25—35

FIG. 2

FIG. 1

FIG. 4

FIG. 3

FIG. 5

FIG. 1 is a front elevational view of a portable computer room or similar article showing my new design;

FIG. 2 is an elevational view taken from the right side thereof;

FIG. 3 is a rear elevational view taken from the left side thereof;

FIG. 4 is an elevational view taken from the left side thereof; and

FIG. 5 is a top plan view thereof.

I claim:

The ornamental design for a portable computer room or similar article, as shown.
